UNITED STATES PATENT OFFICE.

RICHARD JAMES LORE, OF ROCKVILLE, INDIANA, ASSIGNOR OF ONE-FOURTH TO JOHN H. DAVIS, OF JUDSON, INDIANA, AND ONE-FOURTH TO EDWARD DAVIS, OF ROCKVILLE, INDIANA.

POWDER-KEG.

No. 918,875.

Specification of Letters Patent. Patented April 20, 1909.

Application filed November 6, 1907. Serial No. 400,977.

To all whom it may concern:

Be it known that I, RICHARD JAMES LORE, a citizen of the United States, residing at Rockville, in the county of Parke and State 5 of Indiana, have invented a new and useful Improvement in Powder-Kegs, of which the following is a specification.

This invention relates to powder kegs, the object being to provide the keg with a dispensing spout, to one side of the filling opening, so that the powder can be readily 10 poured out of the keg to the cartridge.

Another object of my invention is to slidably mount the spout in the keg, so that 15 when it is not in use it can be moved into the same so as to be out of the way.

A further object of my invention is to provide a slide which will cover the filling opening and spout so as to completely close the 20 opening, thereby preventing any sparks from entering the keg and igniting the powder.

A still further object is to provide a keg with a spring for forcing the spout outwardly as soon as the slide is drawn from over the 25 same.

With these various objects in view, the invention consists in the novel features of construction, combination and arrangement of parts, hereinafter fully described and pointed 30 out in the claims.

In the drawing forming a part of this specification:—Figure 1 is a perspective view of my improved keg showing the spout forced outwardly. Fig. 2 is a vertical sectional view 35 of the keg showing the slide forced over the filling opening and dispensing spout. Fig. 3 is a top plan view of the keg showing the slide drawn from over the spout and opening.

In the drawing A indicates an ordinary 40 powder keg provided with a filling opening A' in its top and a dispensing opening A² arranged to one side of the filling opening and adjacent the edge of the cam. The plate B is secured on the top of the cam over the 45 opening and is provided with flanged edges forming guide-ways, in which is mounted a slide C. The plate being provided with openings B', B² registering with the openings A', A², and mounted in the openings A² B² is 50 a dispensing tube D provided with flanged

upper and lower edges, the tube being slidably mounted therein, so that it can readily work up and down in the same and is normally held within the tube by the slide which completely closes the filling opening and tube when forced over the same. The tube being forced outwardly by a spring E which is secured to the side of the cam and engages the flanged lower end of the tube, so that when the slide is drawn from over the tube 60 the tube will be forced outwardly so that it will fit tightly about the cartridge, without exposing the powder at all.

From the foregoing description it will be readily seen that I have provided a very 65 novel keg with a dispensing spout which is so mounted in the keg that it is out of the way when not in use, thereby preventing it from being dented or broken off, and one which will enable the miner to fill the cartridges 70 without wasting any powder at all, thereby saving a great amount of powder and lessening the danger.

Having thus fully described my invention, what I claim as new and desire to secure by 75 Letters Patent is:—

1. A powder keg with spaced openings in its top, a plate secured over said openings provided with openings corresponding with the openings of the keg and flanged edges 80 forming a guide way, a dispensing tube provided with flanged upper and lower ends slidably mounted in one of said openings a spring arranged within said can normally holding said tube in an extended position and a slide 85 mounted in the guide way of the plate for closing said tube and opening.

2. The combination with a keg provided with spaced openings in its top, of a plate secured on said top over said openings provided 90 with corresponding openings, of a spring actuated spout mounted in one of said openings, and a slide mounted on said plate adapted to close said openings and spout, and hold said spout within said keg, for the purpose 95 described.

RICHARD JAMES LORE.
